United States Patent Office

Des. 193,300
Patented July 31, 1962

193,300

HOMOGENIZER

Harold C. Beck, Malden, and Francis C. Kensley, Lexington, Mass., assignors to Manton-Gaulin Manufacturing Company, Inc., Everett, Mass., a corporation of Massachusetts

Filed Apr. 1, 1960, Ser. No. 59,983

Term of patent 14 years

(Cl. D23—1)

Fig. 1.

Fig. 2.

Fig. 3.

FIG. 1 is a perspective view of the homogenizer, showing our new design;

FIG. 2 is a plan view of the homogenizer; and

FIG. 3 is a side elevational view.

The rear end of the homogenizer is substantially plain in appearance except for the louvers.

We claim:

The ornamental design for a homogenizer, as shown and described.
